UNITED STATES PATENT OFFICE.

WILLIAM W. HURD, OF NEWARK, NEW JERSEY.

DESIGN FOR A CLASP.

SPECIFICATION forming part of Design No. 22,338, dated April 11, 1893.

Application filed February 6, 1893. Serial No. 461,268. Term of patent 7 years.

To all whom it may concern:

Be it known that I, WILLIAM W. HURD, a citizen of the United States, residing at Newark, in the county of Essex and State of New Jersey, have invented and produced a new and original Design for Clasps, of which the following is a specification, reference being had to the accompanying drawings, forming part thereof.

10 Figure 1 is a front perspective view of a clasp for retaining scarfs illustrating my design, and Fig. 2 is another perspective view of the same.

The leading feature of my design consists 15 in a waved flag or pennant-shaped outline and undulating surface of the front jaw-plate of the clasp and the general configuration of an emblematic flag or pennant and in a roughly corresponding flag or pennant-shaped 20 contour of the rear jaw-plate of the clasp.

In the design as shown herein, the front jaw-plate A of the clasp has a waved outline of a roughly triangular or "burgee" character and an undulating figured surface presenting the appearance of a flying "burgee." 25 The rear edge of the front jaw-plate A has a prolonged staff-like border C, outside a rope-like figure D. The rear jaw-plate B of the clasp has a generally triangular outline corresponding roughly with that of the front 30 jaw-plate A.

I claim—

The design for a clasp substantially as herein shown and described.

WILLIAM W. HURD.
